(57) **CLAIM**

The ornamental design for a vital signs monitor, as shown and described.

DESCRIPTION

FIG. 1 is a front, top, and right side perspective view of a first embodiment of a vital signs monitor showing our new design; FIG. 2 is a rear, bottom, and left side perspective view thereof; FIG. 3 is a front view thereof;

FIG. 4 is a rear view thereof;

FIG. 5 is a top view thereof;

FIG. 6 is a bottom view thereof;

FIG. 7 is a right side view thereof;

FIG. 8 is a left side view thereof;

FIG. 9 is a front, top, and right side perspective view of a second embodiment of a vital signs monitor showing our new design;

FIG. 10 is a front view thereof;

FIG. 11 is a rear view thereof;

FIG. 12 is a top view thereof;

FIG. 13 is a bottom view thereof;

FIG. 14 is a right side view thereof; and,

FIG. 15 is a left side view thereof.

The broken lines shown in the figures are included for the purpose of illustrating portions of the vital signs monitor that form no part of the claimed design.

1 Claim, 15 Drawing Sheets
